UNITED STATES PATENT OFFICE.

JABEZ WILKINSON, OF FALL RIVER, MASSACHUSETTS.

WARPER OR SECTION BEAM HEAD.

Application filed January 24, 1927. Serial No. 163,122.

My invention has reference to an improved warper or section beam head which may be applied to the warper beams now in use, which not only serves to maintain the yarn on the barrel but also operates to support the barrel in conjunction with the shaft or gudgeon so as to offset the danger of knocking the parts out of true with one another during the course of the rough handling of the section beams.

A warper or section beam is used on a warper machine to wind on an even sheet of yarn from spools, said sheet consisting of varying numbers of ends, ranging from 350 to 500 ends, and in length from 21,000 to 30,000 yards, in preparation for the slasher or sizing machine which in turn is put on warp beams for the looms. In the usual construction these section or warper beams comprise a hollow barrel built up of wooden lagging with an iron shaft or gudgeon running through the center, said shaft being threaded on each end, with nuts and washers to fasten on the heads or flanges and are made from 8" to 12" diameter and 54" long between heads. The heads or flanges are not rigidly secured to the barrel but are held in frictional contact to allow of relative movement.

It is very essential that these beams run true, otherwise they will strain the yarn and cause excessive breaking of ends, causing bad work and seconds in all following processes. It has always been the practice to make these heads or flanges with a smooth face having holes in their centers to accommodate the shaft or gudgeon to facilitate the turning or changing the position of the heads or flanges to balance the beam. It is customary in

filling these warper beams with yarn to leave the yarn below the outer peripheries of the heads, flanges or when the beam is full, so that the beam can be rolled on the floor without damaging the yarn when moving the beams from one machine to another. In moving these beams, a low two wheel tilting truck is used and when unloading, the front end of the beam is rested on the floor and the other end is lifted or rolled from the truck by the section hand. These beams when full of yarn weigh between 400 and 700 pounds each and when dropped too heavily on the floor the flanges or heads are knocked out of true with the barrel sometimes bending the shaft or gudgeon which is the only support for the beam head. The

force of the impact is transmitted directly and solely to the shaft which under the weight of the yarn usually undergoes bending or breaking away of the internal support. 60

It is an object of my invention to provide an improved beam head of simple but sturdy structure which effectively resists the untruing of the section beam which has application to the old forms of warper beams as well as to new ones. 65

Another object of my invention is to provide a reinforcing beam head by adding a wooden disc or angle ring riveted or screwed on the inside face of the beam heads adapted to fit snugly on the inside of the beam barrel, thereby to transfer the shock from the head or flange to the barrel of the beam which is in turn reinforced by the yarn wrapped 75 therearound.

A further object of my invention is to provide a support for the end of the barrel when empty beams are stacked up on top of one another so that the ends of the lagging 80 are not sheared off as does happen with the usual construction where the ends of the lagging are unsupported.

A still further object of my invention is to provide a circular wedge screw means for 85 gripping and centering the shaft in the barrel.

Other objects and advantages will appear from the detailed description which follows:

I attain these objects by the mechanism 90 shown and illustrated in the drawing wherein:

Figure 1 is an elevational view of an end portion of a section beam, showing the improved beam head having a sheet metal inner face with an angle ring attached thereto. An improved inner support of laminated wood is also shown together with the circular wedge screw for reinforcing the same. 95

Figure 2 is an elevational view of an end portion of a beam head showing a modified form of my improved beam head wherein the head is constructed of laminated wood and a wooden disc disposed on the inner face of the head, said head being used in conjunction with the conventional form of beam barrel. 100

Figure 3 is a vertical cross sectional view of the laminated wooden head shown in Figure 2. 105

Figures 4 and 5 are an outer face and vertical cross sectional views respectively of

the improved beam head shown in Figure 1, the same being of an artillery wheel construction with a sheet metal covering on its inner face, said sheet metal extending over the rim 5 of said wheel.

Figure 6 is a perspective view of the circular wedge screw shown and referred to in Figure 1.

Referring to Figure 1 of the drawings, 1 is 10 my improved beam head with the angle ring 2, 3 the barrel, 6 the shaft or gudgeon, 4 the laminated internal support for the barrel and 5 the circular slotted wedge screw for clamping and holding shaft firmly in center 15 of barrel and reinforcing the support 5, and 7 the end nut. In Figures 4 and 5 this improved beam head is shown on a larger scale and more clearly.

Essentially the beam head is built up on 20 the order of an artillery wheel having the spokes 8 meeting in a common center and held together by the hub plate 9 on one side thereof which will be called the outer side. The other or inner side of the wheel is 25 covered with a sheet metal facing 10, the sheet metal extending over the ends of the spokes to a point on the outer side just below the spoke ends whereby an annular continuous rim 11 is formed with a groove for 30 a friction band or rope. On the inner face or side of the wheel thus formed is secured an angle ring 2 which is concentrically disposed with the wheel. This angle ring may 35 be secured by riveting, welding or in any other suitable way. The size of the angle ring is such as to fit snugly within the ends of the barrel 3. The angle ring is secured to the wheel at its base or plane surface 12 and the barrel fits onto the cylindrical surface 13 40 of the angle ring.

The improved internal support 4 for the barrel is constructed of laminated wood and has an opening in its central portion to receive the shaft or gudgeon 6. The number 45 of these internal supports that may be used is arbitrary and may be left to the manufacturer. A common disadvantage with the prior art wooden internal support is that because of the fact that in ordinary construction (see Figure 2) the diameter of the central opening 19 of the support 20 is much 50 larger than the diameter of the shaft, the supports are centered on the shaft by being secured to an iron flange 21 at each end of the barrel. This securement is generally by 55 screws 22 and the iron flange is held in position on the shaft by a set screw 23. In actual use, however, this construction has 60 not proved reliable for the reason that the jolts and impacts to which the barrel is subjected while in use cause the screws 22 to work loose and lose their holding grip. As 65 a consequence the internal supports descend on the shaft since the opening 19 is much larger than the shaft, and the entire struc-

ture then becomes clumsy and cumbersome. Another evil with this old construction is that the set screw 23 often works loose and rolls around inside the ends of the barrel wearing away a channel in the interior of 70 the barrel by the continual rolling until the end of the barrel is broken off. I have found that by the use of a circular slotted wedge screw these evils may be avoided entirely. The screw shown in Figure 6 is a 75 tapered cylinder having a smooth interior and a threaded exterior 14. A longitudinal slot 15 is provided to allow it to grip the shaft. The screw is used by sliding it on the shaft and screwing the end having the 80 smaller diameter into the central opening in the internal support whereby an iron to iron contact is obtained which is strong and preserves the original diameter of the shaft opening. One of these screws may be used 85 with each of the internal supports.

The barrel 3 is the conventional type being made of wooden lagging 16 secured together to the internal supports.

Although in Figure 1, my improved beam head is shown in conjunction with the improved internal support it should be understood that the beam head is operative with and applicable to the old construction. The barrel snugly fits onto the cylindrical surface presented by the angle ring and the exterior of the barrel is smooth throughout from beam head to beam head. This smoothness is important since any irregularities such as filets will cause uneven strains on 90 the yarn at the ends of the barrel or wherever the filets are located. It will be appreciated that when during the course of handling a beam, the beam is thrown down, the force of the weight of the yarn will be distributed between the angle ring of the head and the gudgeon, the major part falling to the lot of the angle ring. In the beam head now in use this burden is borne by the shaft alone which often and usually results in the 95 bending of the shaft as well as discentering of the internal supports as above stated. 100

The improved head may be used with a barrel having my improved internal supports or the usual construction shown in Fig. 2. 110

In Figure 2 is illustrated a modification of my beam head showing the same constructed from laminated wood 17 and further showing its use in conjunction with the usual beam barrel structure. As better 120 shown in Figure 3 this wooden wheel has disposed thereon on one side thereof a concentric wooden disc 18 of a diameter commensurate with the internal diameter of the beam barrel to allow of a snug fit within the 125 barrel ends. In use the effect and operation of this wooden form is the same as the embodiment above described.

Although I have mentioned the use on the beam head of annular supporting means 130

of a continuous nature, it should be understood that an annular means of a discontinuous nature will be serviceable although possibly not so well. Studs, lugs, or bosses 5 may be disposed on the inner face of the beam head in the path of a circle concentric with the beam head and so disposed as to fit within and support the barrel ends.

The manner of use of my improved barrel 10 end and its mode of operation are apparent by an inspection of the drawings particularly in view of the description above given and further remarks on these points are here considered to be unnecessary.

15 A further feature of my improved beam head is that when associated with the barrel it provides through the medium of the angle ring or annular means, a support for the ends of the lagging. This becomes of im- 20 portance in connection with the stacking and storage of unfilled beams when it is customary to stagger the beams one on the other, the beam head of one resting adjacent the beam head of the lower beam on the end of 25 the barrel lagging which in the usual construction is unsupported save for a slight frictional contact with the beam head. It is not infrequent that during the stacking of these beams these unsupported ends of 30 the lagging are sheared off. In my improved construction this shearing cannot take place inasmuch as the ends of the lagging rest solidly on the annular means provided on the inner face of my improved beam head.

All that has been said above in the description of my preferred embodiment is offered by way of illustration and not limitation. I do not wish to be limited to the exact structure of the preferred embodiment shown and described, or to any particular material used in the construction of parts, or to the design of parts, but desire protection as against any variations in structure which utilize the principle of my invention and fall within the purview of my invention and are within the spirit and scope of the following claim. 35 40 45

The invention having been set forth, what I claim as new and useful is as follows:

An improved warper beam comprising in combination head members, barrel member, internal supports for said barrel member, a gudgeon passing through said head and barrel members, said internal supports comprising disc members of substantially the same diameter as the interior of said barrel member, said disc members being mounted on said gudgeon and disposed within said barrel member, said head members having means thereon for projecting into and supporting the ends of said barrel member, and a longitudinally slit tapered cylindrical screw having a bore therein to slide on said gudgeon and threads thereon for securement to each of said internal disc members. 50 55 60

Signed at Fall River in the county of 65 Bristol, State of Massachusetts, this twentieth day of January, 1927.

JABEZ WILKINSON.
